(57) **CLAIM**

The ornamental design for a servo amplifier, as shown and described.

DESCRIPTION

FIG. 1. is a first perspective view of the front, right, and top sides of a servo amplifier showing our new design;

FIG. 2. is a second perspective view of the rear, left, and bottom sides thereof;

FIG. 3. is a front view thereof;

FIG. 4. is a rear view thereof;

FIG. 5. is a left side view thereof;

FIG. 6. is a right side view thereof;

FIG. 7. is a top plan view thereof;

FIG. 8. is a bottom view thereof;

FIG. 9. is an enlarged view of 9-9 part in FIG. 1 thereof;

FIG. 10. is an enlarged view of 10-10 part in FIG. 5 thereof;

FIG. 11. is an enlarged view of 11-11 part in FIG. 6 thereof; and,

FIG. 12. is an enlarged view of 12-12 part in FIG. 7 thereof. The broken lines shown represent portions of the servo amplifier and form no part of the claimed design.

1 Claim, 12 Drawing Sheets
